CASPAR E. HOFBAUER, OF NEW YORK, N. Y., ASSIGNOR TO PARAMOUNT CARBURETOR CORPORATION, OF NEW YORK, N. Y., A CORPORATION OF NEW YORK

CARBURETOR

Application filed May 2, 1928. Serial No. 274,423.

My invention relates generally to a fuel feeding arrangement whereby a mixture of air and a fuel having a ratio which is most efficient for varying operating conditions is supplied to an internal combustion engine in accordance with the requirement of such conditions, and in one of its phases relates to an arrangement whereby fuel from a distant storage chamber may be supplied to a level adjacent the internal combustion engine, rendering it suitable for forming the air and fuel ratio in accordance with the requirements previously mentioned.

In its more particular embodiment my invention contemplates the provision of a fuel feeding device at a level substantially adjacent the point of consumption of an internal combustion engine and means to supply fuel to such constant level device from a fuel supply chamber at a point distant from said constant level device, the feeding of the fuel to the constant level device being operable by a carbureting system capable of preparing a constant ratio mixture of air and fuel, the carbureting system including a primary mixing device for air and fuel serving to lift the fuel from the constant level storage chamber and feeding the primary mixture so prepared to a secondary mixing chamber, the ratio of air to the supply from the primary mixing chamber being obtained by the air control valve responsive to variations in suction conditions of the engine in the nature of a gravity valve, said valve being free from inaccurate responsive action by the provision of means to overcome the inertia of static or moving parts. It is further contemplated by my invention to associate with a carbureting system including a primary mixing chamber capable of lifting fuel and a secondary mixing chamber utilizing the fuel as prepared in a primary mixing chamber, the fuel being prepared in a secondary mixing chamber being converted into a mixture having a constant air-fuel ratio adapted for internal combustion engine use in accordance with all variations in the suction conditions of the engine, characterized by the provision of an air responsive gravity valve, the fuel for the carbureting system, and particularly for the

primary mixing chamber being obtained by a constant level intermediate storage chamber deriving its fuel supply from a distant fuel storage tank, the supply so obtained being influenced by a diminished pressure head created in said intermediate storage chamber, the diminished pressure head being effected by the engine suction.

In another of its phases, the invention contemplates the provision of a carbureting system having a primary mixing chamber, a secondary mixing chamber utilizing the fuel prepared by the primary mixing chamber, and an air apportioning valve responsive to all variations in the suction conditions of the engine, to be operated at all times to convert the basic mixture into the final mixture, the device including a priming arrangement for supplying fuel for starting purposes and evacuating means for an intermediate storage chamber whereby a constant level fuel supply is provided for the primary mixing chamber and the engine priming device. The invention still further contemplates an evacuating device for an intermediate constant level storage chamber which is free from any tendency to flood due to the inertia of the flow of liquid fuel.

To attain these objects and such further objects as may appear herein or be herein-after pointed out, I make reference to the accompanying drawings forming a part hereof, in which

Figure 1 is a partial cross-sectional elevation through the main elements of my carburetor;

Figure 2 is a partial plan view thereof;

Figure 3 is a plan view of a further embodiment of my invention;

Figure 4 is a section taken on a line 4—4 of Figure 3.

Making reference to the drawing, and particularly Figure 1, I have shown the main elements of my carbureting system in which the portion A may be designated as a primary mixing device, the portion B as the secondary mixing chamber, the portion C as an intermediate liquid fuel supply chamber. The assembly so described is adapted to be connected at a point adjacent an internal

combustion engine, specifically with the intake manifold of an internal combustion engine, fuel being supplied to the carbureting system from a distant low level fuel supply tank, such as the gasoline tank carried on an automobile at the rear thereof.

Referring now to the primary aspirating and mixing device A, this is generally connected to a flanged element 10 extending from the main casting 11. One embodiment contemplates the provision of an air intake element 24 provided with a forwardly projecting nozzle 25, a portion of the outer wall of the latter being externally threaded to engage with the branch 26. It is contemplated that the atmospheric air will enter into the element 24 and will be drawn through the nozzle 25. The branch 26 has a bore therethrough 27, into which is fitted the member 28 which comprises two conical borings 30 and 31, converging towards the central portion to a more restricted junction 32 which, however, presents a slightly larger opening than the restricted discharge 25' through the element 25.

The branch 26 is part of a side wall of the main casting which is enlarged at 29 to receive the member 24, forming with the conical portion 30 an annular chamber 33 about the outside of the nozzle 25. A boring 34 longitudinally of the branch 26 connects with this chamber for the supplying of liquid fuel thereto from the fuel chamber C by the enlarged line 34' and cross boring 35 therebetween, leading to the chamber. There is interposed a metering jet 35' between the two borings 34 and 34' for purposes as will be readily understood.

The chamber C comprises what may be termed a constant level device and includes a receptacle 36, having a cap 37, including an inlet 38, depending downwardly into the receptacle. The portion 38 serves to guide and sustain the float 39 concentric therewith. The float 39 may move freely vertically upon the inlet 38 but is prevented from mounting clear to the top by the skirt 39'. There is also provided at the lowermost portion the bearing 40, in which are mounted the trips 41, pivoted at 42. It will be observed that the float may be free from the terminals 43 of the trips or rest upon them, serving to pivot the inner portions 44 about the pivotal portion 42. The upper portion of the cap has an upstanding flange 45, through which there is drilled an orifice 46, diametrically thereof, as more clearly shown in Figure 1. Over this flange I provide a cap 47 having an inlet flange 47' cooperating with the outside of the flange 45 to form an annular chamber 48. It will be observed that through the inlet of the cap 47 fluid may enter about the annular space 48 and conduct it through the orifices 46 downwardly through the flange 45, centrally whereof an inlet orifice 49 is positioned.

In the chamber formed by the flange 45 and the cap 47, a circular screen 50 is disposed, serving to protect the ingress of particles through the orifice 46, as will be understood. Extending into the orifice inlet 49 and serving to close the same, I provide a spring pressed valve 51, having a conical head 52, with its narrow portion downwardly disposed, the upper whereof has a stem 53 serving to sustain a spring 54, maintained in position by the plug 55, having an inner portion thereof 56 threaded and engaging the flange 45, previously. An exterior flange 57 serves to seat upon the cap and hold the same tight against the loss of fluid by the provision of a gasket 58. The shaft of the valve 51 previously described, is guided to be freely movable vertically within the inlet pipe 38 and to maintain the same in proper position, a bearing 59 is provided. The lower end of the shaft 51 has an enlarged head 60 which serves to engage the inner branches of the tripping members at 44.

It will be observed that with the chamber 36 full of fluid, the float 39 will float to the top and unweight the free end of the trips 43. In this position the valve 52 will be free to be actuated by the spring member 54 to seat the head 52, serving to close the inlet orifice 49. It will thus be observed, by this construction, that a predetermined quantity of fuel or fluid will be maintained within the chamber 36, which is withdrawn through the boring 35, at the bottom thereof. For permitting ingress or air into the chamber 36 at predetermined rates, I preferably provide in the cap 37 an air vent 64, connecting with the vertically drilled orifice 64'. This vent is formed at the base of the boss 65, which is centrally drilled at 66 and screw threaded to retain the needle valve 67 for controlling the ingress of air through the orifice 64'. A spring 68 serves to give the necessary frictional resistance to the needle valve between the base 65 and the knurled head 69, assuring a predetermined setting.

Preferably adjacent the vent previously described an additional air inlet may be supplied and for this purpose the boss 65 has an outwardly directed flange 82 interiorly drilled at 83 to connect with the orifice 64'. The outer end of the flange 82 is interiorly screw threaded at 84 to receive the fitting 85, comprising a screw-threaded sleeve interiorly orificed at 86 with a constricted opening at 87, connecting with the orifice 64' leading to the top of the chamber 36. Vents 88, cross drilled through the fitting 85, connect the interior portion 86 to the atmosphere. A plug 89, frictionally disposed by the spring 90 with the fitting 85 has a boring 91 guiding the rod 92, having at one end thereof the conical valve 93 seating upon the orifice 87; the opposite end is threaded and serves to maintain the valve upon the seat by interposing a

spring 94 between the lock nuts 95. Thus predetermined pressure may be exerted upon the valve 93 upon its seat.

It will be observed that the bore through 5 the fittings 24 and 26 gives a change of velocity to any material flowing therethrough and for this purpose in my preferred form, this bore is made in the form of a Venturi tube. The venturi is made up in part of the nozzle 10 25 and the bore 31, which communicates with the main casting. It will be observed that the nozzle 25 is so constructed as to be spaced from and project into the conically bored portion 30. It will be further observed that 15 an annular chamber 33 is thereby produced, encircling the end of the nozzle 25 and communicating with the space between the constricted portion 25' of the nozzle and the constricted portion 32.

20 Before proceeding with the more detailed description of the other elements of the carbureting system, the operation of the primary lifting means and the primary aspirating device will be elaborated. The invention con- 25 templates the provision of a substantial suction and flow through the venturi formed on the members. This flow not only draws air inwardly through the opening 24 and through the nozzle but it serves to form a diminished 30 pressure head in the annular space 33 and thereby also the connecting line 34. This diminished pressure head serves to draw fuel in liquid form through the downwardly disposed inlet 34, connecting with the line 35.

35 The reduced pressure head of this line is also utilized to form a diminished pressure head through the line 35a in the chamber 36. The fuel passing through the pipe 35 is then drawn through the restricted opening or jet 40 35' into the chamber 33 formed between the fittings 24 and 26. This chamber, it will be observed, is so formed as to take the form of a hollow inclined annulus, to cause the fuel to become discharged into the venturi at the 45 point 32, which is the narrowest part of the venturi and there meets with and is accelerated by the flow of a solid column of air through the nozzle 25. As a result of this arrangement, to which I apply the term primary lifting and aspirating means, not only is 50 a mixture of air and gas formed of substantially uniform character but the fuel is caused to assume a finely comminuted condition and to be mixed with air in a manner so as to 55 form a suitable primary mixture. The parts of my carbureting system are so arranged and constructed that this primary mixture of air and gas is of a character too rich to be employed for ordinary engine operation 60 and I will now proceed to describe the manner in which the primary mixture is converted into a mixture which is uniform as to its ratio of fuel to air and which is fed to the engine at a rate in accordance with re- 65 quirements under all running conditions.

Referring now more particularly to the right hand portion B of Figure 1, it will be observed that the forward end of the fitting 28 is suitably associated with and connected to a main casting or member 70 by a driving fit or by being threaded through the branch 70 26, integral with the casting 11.

The fitting 28 is so arranged with respect to the casting 11 as to direct the primary mixture into an annular chamber similar to but 75 larger than that of the annular chamber 33 of the primary mixing device shown at B. Part of the primary mixture is diverted through the orifices 31' and part through the end of the fitting 28. This chamber will be hereinafter referred to as the secondary mixing chamber and constitutes a portion of the secondary mixing or controlling device hereinbefore referred to, tending to perfect the mixture first formed.

The secondary mixing chamber is constituted by an upwardly disposed annular member 72, mounted with an inwardly directed flange integral with the casting 11 and arranged slightly below the fitting 28. The 80 member 72 tapers upwardly and is of a length preferably to be in the direct path of the fuel coming in through the fitting 28 to have its edge 72' in substantial alignment with the lower edge of the fitting 28 which extends 85 diametrically and substantially to the center of the fitting 72. Within the upper portion of the casting 11 is arranged a tubular fitting or bushing 73 whose lower edge 73' is just slightly spaced from the member 72 and the edge 72'. The members 72 and 73 have outer conical walls 90 and 76, respectively, forming an annular chamber 74' with an outlet slot 74 formed by the spaced edges 72' and 73', respectively. The fuel from the end 95 of cone 31 feeds the primary mixture in line with this slot and for the purpose as will be more clearly described, presently, this edge is angularly cut at 28'. Above the bushing 73 the casting 11 is provided with a flange 100 80, adapted for connection to the intake manifold of the engine in any of a number of well known ways and within the upper portion of the casting the usual throttle valve 105 85 is provided.

With a diminished pressure head within the chamber 36 as induced by the line 35a and with no fluid in the chamber, the inlet 49 will be open, thereby permitting fuel to be drawn into the float chamber 36 from 110 some distant supply chamber as the rear tank of an automobile through a line connected with the flange 47'. The path of the fluid will thereafter be through the orifices 46, downwardly through the flange 45, serving 115 120 to fill the chamber 36. As the float rises within the chamber, the trips 41 will permit the spring pressed valve 51 to become seated, cutting off any further addition of the fuel thereto and preventing flooding of the cham- 125 130

ber 36. The vent 64 giving an opening to the atmosphere within the chamber, will re-establish normal atmospheric pressures therein and will permit the withdrawal of liquid fuel from the chamber through the line 35 5 in a manner which will be readily understood.

Should the diminished pressure within the chamber 36 be in excess of that necessary for maintaining a constant supply of fuel in the 10 chamber, as occasioned by the differential resulting from the sizes of the vent 64 and that of the line 35a, as may be occasioned by a very rapid increase in the vacuum within the line 35a, the fitting 85 and its assembly have 15 been provided. Thus a sharp increase in vacuum may be equalized within the chamber 36 above the fuel, permitting the free flow of fuel through the orifice 35, by adjusting the valve spring 94 to predetermined 20 pressure, to admit air through the orifices 88 if a greater vacuum is created.

Before describing in detail the automatic operation of the elements, it may be explained that it appears that under all conditions of 25 operation additional air is drawn upwardly through the members 72, under controlled condition, by the suction produced within the intake manifold. This air attains a great 30 velocity at the upper end of the members 72, as it will be readily understood that the mixture which has been caused to whirl around the secondary mixing chamber will be picked 35 up and directed through the fitting 73, along with this additional air entering through the member 72. Additionally, mixing and vaporizing will occur as the mixture passes 40 through the annular chamber 74', and then through the slot 74.

The controlling device comprises a conical 45 valve 167, normally raised by gravity, closing an opening formed by an internal flange 175 below the member 72 and a conical extension 175' immediately above the same. The flange 175 constitutes the upper wall of an air intake element 176 which is substantially cylindrical and is provided with a duct 177 for the admission of air. The intake element 176 is considerably larger than the intake element 24, as is the duct 177 with respect to the 50 opening 25' and it will be understood that the main portion of the air necessary for the formation of a proper mixture is supplied through the element 176.

The valve 167 is more or less controlled in 55 its movement by the dash-pot arrangement shown as carried below the element 176. More particularly, I prefer to provide a chamber 180 adapted to contain liquid, and I have shown the valve 167 provided with a 60 downwardly projecting stem 181, the latter being slidably mounted within a bearing portion 182 depending from the lower wall 183 of the air intake 176. At its lower end the stem 181 is provided with a piston 184 or the 65 like, presenting an increased area to the liquid

whereby the movement of the valve 167 will be suitably retarded and damped.

The dampening piston 184 has associated therewith a secondary piston 185 in the form of a thin disc of large diameter and arranged to prevent a greater retarding surface and has a lost motion connection with the stem 181 as follows: The secondary piston 185 is received in a reduced portion of the piston 184 so as to permit of a free limited movement of the secondary piston 185. Spacing circular spurs or ridges 186 and 187 serve to hold the disc 185 away from contact with the primary piston 184. The effect of this two part damper is to provide a greater initial 80 retardation of the upward movement of the valve 167 than on the downward movement thereof, because on the upward movement of the valve 167, the pistons 184 and 185 will move together from the time of initiation of such movement, whereas on the downward movement of the valve 167, the stem 181 and the piston 184 will move relatively to the piston 185 at the beginning of the movement.

The disc piston 185, as will be observed 90 upon viewing Figure 1 of the drawing has its inner edge so dimensioned and arranged as to fit loosely on the piston 184 so as to provide a clearance between this edge and the adjacent wall of the piston. The outside edge of the piston 185 is however so arranged as to provide a rather close fit inside of the wall or skirt 116 of the chamber 180. Inside of the upper circular ridge 186, the piston 184 is provided with one or more openings 184', 100 therethrough.

As a result of this arrangement, it will be understood that not only is the disc piston 185 self-aligning and always true as to its 105 position in the chamber 180 but also upon the unseating of the disc piston 185 from its position as shown in the drawings, which occurs on the downward movement of the piston 184, a free passage is provided through the opening or openings 184' and through the clearance around the inner edge of the piston 185 to beneath the piston 184. In this way, the downward movement of the piston is caused to be made more quickly than the upper movement under the same character 115 of impulse.

It is of course desirable that the starting mixture have an increased richness, and in order to control the continuation of this supply of relatively rich mixture, the valve 167 may be arranged and constructed to permit 120 manual control thereof. For this purpose, I may employ a manually controllable lever 117, the outer end of which may be operated by a lead 118, of which a spring 119 forms a part, from a suitable point on the dash-board 125 so that it may be controlled. The inner end of the lever is arranged to engage the upper end of the valve 167. In this manner, what 130

amounts to an increased weight may be given to the valve.

Once the engine has started, the suction will immediately operate to lift the valve 167 off of its seat. This lifting movement will be initially retarded by the piston 184 and the amount of opening produced by the valve 167 will depend upon the speed of the engine. At any constant rate of speed, the valve 167 will flutter or float at a predetermined point, to permit the admission of a predetermined amount of air through the duct 177. It will be understood that the valve 167 will remain off its seat in all conditions of engine operation.

It will therefore be seen that a vacuum will serve to provide a primary or basic, somewhat vaporous mixture throughout the running period of the engine. The parts are so proportioned and arranged that this initial mixture is richer than that required for normal automobile engine operation, and it will be observed that the secondary mixing chamber accomplishes the function, among other things, of reducing the richness of the mixture.

It will be further observed that the final richness is controlled by the amount of air supplied through the duct 177 instead of by a needle valve of the usual type which controls the amount of gasoline. Inasmuch as a suitable mixture comprises proportions of air and fuel in the neighborhood of 14 to 1, it will be obvious that the control of the "14" factor instead of the "1" factor will render inaccuracies of design and maladjustment of parts less effective in causing defective operation, I consider this an important feature of my invention.

Another feature which I consider of great importance is the arrangement whereby fuel in sprayed or vaporized condition is picked up from an annular chamber by air passing through said chamber in an axial direction. This feature will be clearly observed in connection with both the primary and secondary mixing chambers, and it will be obvious to those skilled in the art that an arrangement of this character is fundamentally different from that employed in connection with the ordinary carburetor in that conditions are attained wherein the flow induced by the intake manifold is more accurately proportioned between air and fuel or air and fuel mixture because each agent is conditioned or prepared to be more readily responsive in supply.

A particular feature of the present invention resides in utilizing gasoline as the retarding liquid within the chamber 180. For this purpose, the bottom of the chamber 180 is provided with a line 190 included by the elbow 191 as one arm and the branch 192 as the second arm, to which latter member is connected the tube 193 extending into the chamber 34' with its end 194 below the jet 35'

but well above the orifice 35 of the chamber 36. A fitting 195 serves to maintain the tube 193 in position in the concentric position. At the bottom end 196 of the tube a ball valve 197 is normally held to close the tube by the spring 198, and the plug end and seal 199. It will be observed that the end 194 of the tube is positioned so that at no time will there be a complete overflow of liquid fuel from the chamber 36 to the chamber 180. This position further assures a minimum low level to the top of the tube in the channel 34'.

From above the piston 184 within the chamber 180, a line 200 is connected with the orifice 34. Thus liquid fuel may be conducted from the chamber 180 to primary mixing chamber as will appear presently.

A particular advantage which is gained by utilizing gasoline as the retarding fluid lies in the fact that this fluid may be utilized in modifying the richness of the mixture at certain critical periods of the running of the engine. When the engine is suddenly accelerated, the valve 167 will tend to leap upward with a certain amount of suddenness. Normally, this would tend to produce a momentary unduly lean mixture. While a too sudden upward movement of the valve is retarded by the piston 184 and the plate 185, the richness required for this quick acceleration is attained by me as follows: As the valve moves upward quickly, a small amount of fuel is forced from the chamber 180 above the piston 184, through the passageway 200 and into the orifice or line 34. This temporarily increased richness is extremely advantageous, inasmuch as it will be noted that this increase in richness occurs at exactly that period of running when it is most needed, namely, during rapid or instantaneous acceleration. It will also be noted that this temporary raising of additional rich liquid fuel will be but momentary. It will be observed that the one way ball valve 196 will act to permit liquid fuel to be drawn in below the piston 184 under rapid movements of the valve 167. Normal overflow or circulation about the piston may be facilitated by the orifice 116'.

Correspondingly, when the engine throttle is suddenly closed, the retarding effect of the piston 184 will prevent choking of the engine by a possible sudden increase in richness due to the shutting off of the air supply. Under these conditions, the ball valve 196 will be seated upon its seat, the end of the tube 196, to prevent pumping of the liquid fuel into primary mixing chamber 33.

Inasmuch as it is important to prevent a sudden rise of the valve when the throttle is suddenly thrown wide open, than it would be to prevent a sudden fall, I have provided the aforementioned lost motion effect between the two part piston 184 and 185.

It will be observed that the top of the valve 167 is dished or depressed at 167' so that any

condensate or excess fuel may collect in this portion and be drained through the orifice 181' which may also serve to supply sufficient air to vaporize the fuel collected in this 5 dished portion upon sudden acceleration.

It will be obvious that in its passage to the point of consumption, the mixture may be preheated as by the exhaust of the engine, thereby preheating the mixture and producing advantages which will be obvious. It 10 will be understood that numerous other arrangements and constructions of parts may be made to fulfill equivalent purposes and I do not mean to limit myself to the particular 15 structural features illustrated and described. Many changes in the details as herein described and illustrated may be made by those skilled in the art without departing from the spirit and scope of the invention as expressed 20 in the appended claims. It is therefore intended that these details be interpreted as merely illustrative, and not in a limiting sense.

The manner in which the fuel is drawn 25 from the rear tank to the chamber 36 is such as to always maintain the quantity of the liquid fuel within this chamber constant, regardless of the height of the fuel in the rear tank and without in any way interfering 30 with the quantity of fuel to be drawn up for mixing in the primary mixing chamber A.

By the arrangement herein disclosed, I find 35 that I attain a primary mixture in which the air and fuel are mixed together so as to provide a mixture which not only is itself stable, but the stability of which is still further increased in its travel to the point of consumption.

One of the important features of my invention 40 is an arrangement whereby a fuel mixture of maximum efficiency is at all times supplied for combustion purposes, and the proportion of fuel and air contained therein is maintained substantially constant regardless 45 of running conditions, the proportion being such as to give the aforementioned maximum efficiency.

Another important feature of my invention 50 is the employment of a gravity valve such as that shown at 167 as the main controlling factor of the character of mixture to be produced because, not only does it control, as already stated, the air which is the large factor of the mixture, but a gravity valve presents a constant load regardless of suction 55 conditions, and therefore moves exactly in accordance with and proportional to the variation in such suction conditions.

The shape of the valve 167 which is herein 60 illustrated as top-like in character, possesses features of advantage in so controlling and directing the flow of air over the flange 175' as to cause it to serve its purposes with great efficiency in connection with the directing 65 of the flow of air so that a maximum

mixing effect with the fuel mixture is produced. It will also be observed that I herein show this valve 167 as positioned relatively close to the constricted passageway through 71 and relatively close therefore to 70 the point at which the primary fuel mixture is introduced from the neck 71, which also I have found possesses features of advantage.

In the embodiment shown in Figures 1 75 and 2, the portions A and C are shown substantially in axial alignment, as will be more clearly apparent from viewing Figure 2. I may, for certain purposes, dispose the portion C containing the constant level float chamber at right angles to the portion A so that the branch 26a is in the plane of the annular chamber 33. The float chamber 36c is connected with the annular chamber 33 by the line 35c serving to cause the formation of a diminished pressure head within the chamber 36c for the purposes of drawing into this chamber liquid fuel from the main rear storage tank, as described in connection with the embodiment shown in Figure 1. Fuel is fed from the float chamber from the bottom orifice 35b upwardly through the line 34c which terminates in a jet 34'c in the line 35c previously described. The top of this jet is substantially just above the maximum level maintained within the fuel storage chamber 36c so that when a diminished pressure head is formed by the primary mixing chamber within the annular chamber 33, liquid fuel will flow upwardly through the jet 34'c, as fed from the line 34c and 35b. The diminished pressure head will also serve to maintain a predetermined vacuum in the line 35c as previously described. From the line 35c, at a point beyond the jet 34'c I may connect a line 200' corresponding to that shown in Figure 1 and numbered 200' for the purpose of maintaining a suitable fuel level in the chamber 180 and for priming purposes, as previously described in the corresponding member shown in Figure 1.

By the arrangement of parts as herein described, the connections between the part A and the part B are made internally of the branch 26c, not only with greater compactness but in a manner permitting the ready supply of fuel from the intermediate fuel storage chamber at minimum diminished pressures, as created within the primary mixing chamber B.

It will thus be observed that I have provided a carburetor which will serve to most efficiently supply fuel for all operating conditions, such as starting, idling, rapid acceleration, rapid deceleration, change of load, 125 hill climbing, all capable of supplying the fuel for operating an internal combustion engine with maximum efficiency from a fuel storage chamber distantly positioned from the point of consumption, as the carburetor, 130

which is adjacent to the internal combustion engine.

Having thus described my invention and illustrated its use, what I claim as new and desire to secure by Letters Patent, is—

- 5 1. In a fuel feeding and carbureting device, in combination, a primary fuel mixing and evacuating device operable by the engine induction, passages thereto, one of which 10 serves to feed fuel from an intermediate fuel storage chamber, the other of which serves to form a diminished pressure head within said chamber whereby fuel from a low level storage tank may be caused to flow into said 15 chamber and a float controlled valve for intermittently shutting off the fuel supply to said chamber, and air valves in said chamber for limiting the diminished pressure head in said chamber within predetermined amounts.
- 20 2. In a fuel feeding and carbureting device, in combination, a primary fuel mixing and evacuating device, operable by the engine induction, a secondary fuel mixing chamber connected therewith, an intermediate fuel chamber, passages from said device to said fuel storage chamber, one of which is above the liquid level, a connection for a low level storage tank and a float controlled valve for said connection, an air passage to said fuel storage chamber of a size as compared to said evacuating device to form a diminished pressure head within said chamber whereby fuel from a low level storage tank may be caused to flow into said 30 fuel storage chamber and means for admitting air to said fuel storage chamber when a predetermined pressure is obtained in said fuel storage chamber.
- 35 3. In a fuel feeding and carbureting device, in combination, a primary mixing chamber comprising conical members having a restricted portion therebetween, a float chamber, passages connecting said float chamber with said primary mixing chamber at the restricted portion, one of which passages is disposed below the normal level of the liquid fuel in the float chamber forming the fuel supply, the other of which is disposed above the normal level of the fuel in 50 the float chamber whereby suction therethrough may cause a flow of liquid fuel to said float chamber from a low level fuel storage tank, a secondary mixing chamber comprising spaced tubular members restricted at adjacent terminal portions, a connection from said primary mixing chamber to said tubular members, an air valve for said secondary mixing chamber, dampening means for said air valve comprising a piston 55 freely movable within a cylinder adapted to retain liquid fuel and connecting passages between said cylinder and said fuel feeding passage.
- 60 4. In a fuel feeding and carbureting device, a primary mixing chamber comprising

spaced conical members connected with an annular chamber, a fuel line and evacuating line connected thereto, said evacuating line being connected with a float controlled intermediate storage chamber whereby fuel may be lifted from the low level storage tank to a point adjacent the intake manifold, said fuel line being connected below the normal level in said intermediate fuel storage chamber.

In witness whereof I have hereunto signed my name this 24th day of April, 1928.

CASPAR E. HOFBAUER.
